UNITED STATES PATENT OFFICE

FRANCIS M. SIMPSON AND ROBERT TERRY, OF STROUD, OKLAHOMA; SAID TERRY AS-
SIGNOR TO SAID SIMPSON

HEAT CONSERVING ATTACHMENT FOR UPRIGHT BOILERS

Application filed March 20, 1929. Serial No. 348,547.

The present invention relates to water boilers, and aims to provide a novel and improved heat conserving attachment for an upright boiler.

5 It is the object of the present invention to provide a novel device to be placed over an upright boiler for compelling the products of combustion to pass down the sides of the boiler in order to assist in heating the boiler, thereby saving fuel.

Another object of the invention is the provision of novel means for mounting and assembling inner and outer shells or hoods over the boiler for the flow of the products 15 of combustion downwardly within the inner hood and upwardly within the outer hood.

With the foregoing and other objects in view, which will be apparent as the description proceeds, the invention resides in the construction and arrangement of parts, as hereinafter described and claimed, it being understood that changes can be made within the scope of what is claimed, without departing 25 from the spirit of the invention.

The invention is illustrated in the accompanying drawings, wherein—

Figure 1 is a vertical section of the device, illustrating the boiler and other portions in 30 elevation.

Fig. 2 is a section on the line 2—2 of Fig. 1, omitting the boiler.

The device is attached or mounted over 35 an upright water boiler 7 which is heated by a gas burner or other suitable heater, and the products of combustion are discharged from the top or upper end of the boiler.

An inner shell or hood 8, having the top 9, is positioned over the boiler, and is supported by a split band 10 embracing the boiler. The ends of the band are connected by a bolt 11 for tightening the band on the boiler, and said band has outstanding brackets 12 on which the lower end of the hood 8 is seated, thereby conveniently supporting the hood from the boiler.

The outer shell or hood 13 is placed over the inner hood, and has legs 14 seating on 50 the floor. The hood 13 has a top 15 pro-

vided with an outlet 16 for the products of combustion.

The lower end of the hood 13 extends lower down than the hood 8, but both hoods are spaced above the floor. The hoods are spaced from one another and from the boiler so that the products of combustion will pass downwardly between the inner hood and boiler and thence upwardly between the two hoods to the outlet 16. The products of combustion surrounding the boiler will assist in heating the boiler, so as to conserve the heat and save fuel.

In order to direct the products of combustion from the inner hood below the lower edge thereof to the space between the hoods, a sleeve 17 embraces the boiler and has a lower outstanding flange 18 spaced below the hood 8 and extending to the hood 13, so as to close the lower end of the outer hood. The sleeve 17 is preferably split in two or more parts so as to be conveniently applied to the boiler, and the sleeve 17 is clamped between the band 10 and boiler to support said sleeve conveniently.

Having thus described the invention, what is claimed as new is:

1. A device of the character described comprising inner and outer hoods to be disposed over an upright boiler, the outer hood extending lower down than the inner hood, a split sleeve to embrace the boiler and having an outstanding flange to close the lower end of the outer hood, and a band to embrace said sleeve for clamping it on the boiler and having brackets for supporting the inner hood.

2. A device of the character described comprising inner and outer hoods to be disposed over an upright boiler, a band adapted to embrace the boiler and having brackets for supporting the inner hood, and means for closing the lower end of the outer hood and adapted to be clamped to the boiler by said band.

3. A device of the character described comprising inner and outer hoods adapted to be removably disposed over an upright boiler, the outer hood extending lower down than the inner hood, and means adapted to

removably embrace the boiler and having brackets for supporting the inner hood and having an outstanding flange to close the lower end of the outer hood.

5 4. A device of the character described comprising inner and outer hoods adapted to be removably disposed over an upright boiler, the outer hood extending lower down than the inner hood, a sleeve to removably embrace the boiler having an outstanding flange to close the lower end of the outer hood, and a band to removably embrace the boiler and having brackets for supporting the inner hood.

10 15 In testimony whereof we hereunto affix our signatures.

FRANCIS M. SIMPSON.
ROBERT TERRY.
